UNITED STATES PATENT OFFICE.

MORLEY PYSON JACKLINE, OF ATCHISON, KANSAS.

TOOL HANDLE.

Application filed May 26, 1925. Serial No. 33,003.

This invention relates to handles for hammers, axes, and other implements for tools which have heads and eyes to receive handles; and it is an object of this invention to produce 5 means for securing handles in the heads of such tools in a manner which will prevent the handles from becoming loose or developing lost motion to a degree which will permit the head to fly off the handle, as so often occurs 10 when provision is not made for retaining the parts assembled.

It is a further object of this invention to produce a head anchoring device, as well as 15 handle strengthening means, so that by simple and inexpensive construction, dual functions are accomplished.

It is a still further object of this invention to produce a device having the object indicated that can be made expeditiously and 20 comparatively inexpensively.

With the foregoing and other objects in view, the invention consists in the details of construction, and in the arrangement and combination of parts to be hereinafter more 25 fully set forth and claimed.

In describing the invention in detail, reference will be had to the accompanying drawing forming part of this application wherein like characters denote corresponding parts in 30 the several views, and in which—

Figure 1 illustrates a view in elevation partly in section of a handle embodying one form of the invention;

Figure 2 illustrates a sectional view on the 35 line 2—2 of Fig. 1;

Figure 3 illustrates a view in elevation of a fragment of the handle with an anchoring device embodying a modification;

Figure 4 illustrates a sectional view on the 40 line 4—4 of Fig. 3;

Figure 5 illustrates a sectional view of a handle embodying a further modification; and

Figure 6 illustrates a view of a fragment of 45 a handle embodying another modification.

In these drawings, 10 denotes a handle shown as applied to a hammer, the handle proper being formed of wood, with a strengthening plate 11 of metal extending 50 longitudinally thereof in a groove which terminates between the ends of the handle and at the outer end thereof.

The edges of the plate are preferably pro-

vided with serrations 12 on those portions that are within the head 13 of the handle and these 55 serrations are intended to increase the frictional engagement of the plate and the wall of the head to insure a firm anchorage. The end of the plate within the head is also provided with longitudinally extending slots 14 60 in which wedges 15 may be driven for the purpose of expanding the plate and forcing it into more intimate engagement with the head. The plate has an aperture 16 to receive a rivet 17, which rivet has its ends anchored 65 in retaining plates 18 that are preferably imbedded in the outer surface of the wooden portion of the handle in order that by the said means the inner end of the plate is retained 70 in its seat, and the said plate serves to strengthen the wooden part of the handle and cause it to be more securely held in the head.

In that form of the invention shown in Fig. 3, the handle 19 has cheek plates 20 preferably imbedded in the sides of the handle and secured in place by fastenings 21 such as rivets. The plates 20, as well as the handle, are, as in the first described construction, provided with slots 22 into which wedges may be driven for 80 expanding them, and preferably the edges of the plates are serrated as shown at 23.

In that form of the invention illustrated in Fig. 5, the handle 24 has a longitudinally extending slot in which a plate 25 is located, the 85 said plate 25 being similar to the first mentioned plate, and the plate 25 has an extension or shank 26 which projects into an aperture 27 in the handle, the said aperture constituting a continuation of the slot. The shank 26 is threaded near its end 28 and it is engaged 90 by a nut 29 whereby the plate is removably secured in the handle. The plate 25 has slots 30 and serrations 31, as in the forms previously described.

Referring to Fig. 6, it will be observed that 95 the handle 32 has a plate 33 which is slotted as at 34 and 35, and in this form of the invention, the plate is distorted at its outer end to assume the dotted line positions illustrated, in which positions they engage the head 100 of the hammer to prevent the withdrawal of the handle therefrom. This form of the invention also includes a camming element 36 which is mounted on a pivot 37 and in such 105 relation to the end of the handle as to be forced into engagement with the head of the

hammer when the handle is inserted in the head. The cam exerts force to press the head against the distorted portions of the plate so that by this means the head is held against moving from the handle.

I claim:

In a tool handle, a handle having a plate at-

tached to it, a cam on the side of the said plate for engaging a head, means for pivoting the cam on the plate, the said plate having slots at its ends, those portions of the plate outside of the slots being distortable for retaining the plate of the handle on the head. 10
